UNITED STATES PATENT OFFICE.

PETER C. SECOR, OF SAN FRANCISCO, CALIFORNIA.

NUT-LOCK.

SPECIFICATION forming part of Letters Patent No. 733,754, dated July 14, 1903.

Application filed April 20, 1903. Serial No. 153,386. (No model.)

To all whom it may concern:

Be it known that I, PETER C. SECOR, a citizen of the United States, residing at San Francisco, in the county of San Francisco and State of California, have invented certain new and useful Improvements in Nut-Locks, of which the following is a specification.

My invention relates to nut-locks, the object of my invention being to provide means which shall be cheap and simple in construction whereby a nut may be securely locked on a bolt to prevent the unscrewing thereof.

My invention therefore resides in the novel construction, combination, and arrangement of parts for the above ends, hereinafter fully specified, and particularly pointed out in the claims.

In the accompanying drawings, Figure 1 is a side elevation of a bolt and nut thereon in the position in which the nut is locked on the bolt. Fig. 2 is a cross-section thereof on the line A A of Fig. 1 looking toward the nut. Fig. 3 is an enlarged detail of part of Fig. 1. Fig. 4 is a view similar to Fig. 1, showing the parts in the position in which the nut is advancing and before it is locked on the bolt. Fig. 5 is a cross-section on the line B B of Fig. 4 looking toward the nut. Fig. 6 is an enlarged detail of part of Fig. 4. Fig. 7 is a longitudinal section of the bolt and nut. Fig. 8 is an end view of the same. Fig. 9 is a detail perspective view of the key. Fig. 10 is a similar view of the spring.

Referring to the drawings, 1 represents the bolt having the head 2 and the screw-threads 3. At the screw-threaded end said bolt has a longitudinal groove or trough 4, partly closed at the end, as shown at 5, in which is placed the sliding key 6. Said key has on its upper surface as it rests in the groove threads or ribs 7, which are at the same distance apart as the threads of the bolt and the forward ends of which have the same pitch as the threads of the bolt, so that when brought into register therewith they form continuations of the same; but the rear ends are cut away or sloped back slightly toward the head of the bolt, as shown at 8. The end of the key 6 next the head of the bolt is reduced in size to form a stem 9, around which is a coiled spring 10, which presses against the end of the groove and the end of the shoulder of the key

from which said stem extends. By this means the key is normally pressed by the spring away from the head of the bolt, so that its outer end presses against the partly-closed end 5 of the groove. In this position the rear portions of the short threads or ribs 7 on the key are in alinement with the threads of the bolt on the rear side of the groove, as shown in Fig. 1.

The nut has one or more longitudinal grooves 11 cut in its inner surface. In the present instance I have shown three such grooves, so that the nut will be locked after each turn through one-third of a revolution. If it is desired to lock the nut after a smaller angular movement, more of such grooves will be provided. If after a larger, then fewer will be provided. These grooves are cut to the depth of the thread or slightly deeper, leaving shoulders 12 at the ends of the threads where they are cut through. When the nut has been turned so that the forward edge of one of said grooves 11 in the nut has passed the sliding key, then the threads of said key finding no resistance to longitudinal movement the key can slide toward the nut under the action of the spring 10, so that its end abuts against the partly-closed end 5 of the groove. In this position the forward ends of the short threads or ribs of the sliding key are out of alinement with the ends of the threads at the front edge of the groove and are in line with the shoulders on the threads of the nut, so that they form abutments for said shoulders, preventing the nut from turning rearwardly. When the nut is now advanced, the shoulders of the threads in the nut at the rear side of the groove can pass into the depressions between the threads or ribs of the sliding key on account of said threads or ribs being slanted backward at their rear portions toward the head of the bolt. The forward movement of the nut will cause the sliding key to slide inward toward the bolt-head against the action of the spring until the groove in the nut is again exactly over the sliding key, when the sliding key will slide outward under the action of the spring and will lock the nut, as before. To remove the nut, any small narrow instrument, such as a small nail or nail-punch, is pushed through the opening between the end of the groove and the nut

against the end of the sliding key, pushing said sliding key inward against the action of the spring into its unlocking position. While it is so held in said unlocking position the nut 5 can be unscrewed and taken off the bolt.

I claim—

1. In a device of the character described, the combination of a bolt having a longitudinal groove, a key movable in said groove 10 having on its upper surface threads or ribs at the same distance apart as the threads of the bolt, the rear ends of said threads or ribs being cut away toward the head of the bolt, and a nut having a longitudinal groove through 15 its threads, whereby after the nut has been screwed onto the bolt the shoulders of the threads of the nut may be brought into alignment with the shoulders of the threads of the sliding key, the latter then forming abutments, substantially as described.
2. In a device of the character described, the combination of a bolt having a longitudinal 20

dinal groove, a key movable in said groove having on its upper surface threads or ribs at the same distance apart as the threads of the bolt, the rear ends of said threads or ribs being cut away toward the head of the bolt, and a nut having a longitudinal groove through 25 its threads, whereby after the nut has been screwed onto the bolt the shoulders of the threads of the nut may be brought into alignment with the shoulders of the threads of the sliding key, the latter then form abutments, and a spring for normally bringing the shoulders of the nut-threads into alignment with the shoulders of the key-threads, substantially as described.

In witness whereof I have hereunto set my hand in the presence of two subscribing witnesses.

P. C. SECOR.
